UNITED STATES PATENT OFFICE.

MILES H. MANN, OF TERRE HAUTE, INDIANA, ASSIGNOR TO INTERNATIONAL MONEY MACHINE COMPANY, OF TERRE HAUTE, INDIANA.

REGISTER ATTACHMENT.

1,273,895.

Specification of Letters Patent. Patented July 30, 1918.

Application filed May 20, 1915. Serial No. 29,354.

To all whom it may concern:

Be it known that I, MILES H. MANN, a citizen of the United States, residing at Terre Haute, in the county of Vigo and State of Indiana, have invented certain new and useful Improvements in Register Attachments, of which the following is a specification.

This invention comprises a registering attachment for money paying machines.

The invention relates to money paying machines of the type wherein suitable coin holders are used with an associated system of ejectors, the latter controlled by selecting mechanism and there being a keyboard or equivalent means the keys of which control the operation of the ejectors so that a selected sum of money may be paid out of the machine by discharging from the holders 20 different denominations of coin going to make up said selected sum.

It has been proposed in the art of money handling and registering machines, preferably for the purpose of making up pay- 25 rolls, to utilize a suitable selective mechanism by which to control a plurality of unit registers one or more of which are operable to register the required number of coins of different denominations, necessary to make 30 up a certain sum of money set up on the machine. As typical of this type of machine reference is made to Griffen Patent Number 979,391, issued December 20, 1910.

Having in view the foregoing, a primary 35 object of the present invention therefore has been to construct a registering mechanism adapted to be applied detachably to a money handling machine, and particularly to the coin holder or magazine section of 40 such a machine in such a manner that without alteration of the money handling machine whatever, the regular operations of setting up transactions by the use of the latter machine will operate the detachable register mechanism through the movement 45 of the ejectors which under normal conditions would discharge the coins from the machine. Thus it is that a money handling machine of the type previously referred to 50 by the application thereto of the denominationalizer attachment hereinafter described may be converted into a special registering machine capable of denominationalizing, by which is meant the dividing up of the sum 55 of a transaction on the machine into the

constituent denominations of money required to make up said sum; or into a special registering machine in which the total value of the amounts required for the purpose of supplying the various holders or coin receptacles, may be obtained preliminary to securing a sufficient amount of coin of the different denominations capable of being received in the holders, for the particular payroll or other purposes for which the machine may be intended to be used.

In the drawings:—

Figure 1 is a front view partly in section showing a money paying and registering machine with the attachment of the invention applied thereto.

Fig. 2 is an enlarged vertical sectional view partially broken away showing clearly the operative relation between one of the registering mechanisms and an ejector when 75 the registering attachment is applied to the coin magazine of the machine.

Fig. 3 is a fragmentary front view of the same, the actuating mechanism within one of the register casing extensions being 80 shown.

Fig. 4 is a fragmentary front view of the attachment showing more fully the means to connect the same with the coin magazine.

Fig. 5 is an end view showing especially 85 the parts illustrated in Fig. 4, and other parts.

Fig. 6 is a sectional view taken on the line 6—6 of Fig. 2.

Fig. 7 is a sectional view showing more 90 clearly the ejector and selector instrumentalities.

Fig. 8 is a sectional view bringing out more fully the connection between the handle and the ejector shaft.

Fig. 9 is a detail view showing more fully 95 the selector operating means intermediate the handle and the selectors.

The money handling and registering machine illustrated in the drawings is of the 100 type shown in the application of White, Overlin and Bullington, Serial Number 702,164 filed June 7, 1912, and comprises the registering section A and the money paying section B. The registering section 105 A embodies a keyboard including the amount keys 29 depressible so as to engage lugs 28 on selectors 20. There is provided a series of selectors 20 for each row of keys 29 and depression of a key is capable of depressing 110

the right hand end portions of one or more 5
selectors 20 according to the value designation of the particular key. The selectors 20 are provided with lugs 21 adapted to engage
5 ejector bails 22, see Figs. 1 and 7, so that a longitudinal rightward movement imparted to a selector 20 will tilt or cause pivotal movement of a bail or bails 22. The selector 20 may have one lug 21 only, in which event
10 a single bail 22 will be tilted, whereas if the particular selector 20 has more than one lug 21 a certain bail 22 for each lug will be tilted. Each bail 22 controls the operativeness of a certain ejector 3, see Fig. 7,
15 said ejector 3 having its front end movable through an opening in the rear wall of a coin receptacle C, a plurality of which are provided in a suitable coin magazine mounted detachably at the front portion of the
20 paying section B of the machine. At its rear end each ejector 3 has a lateral projection 3' adapted by the movement of the associated bail 22 to be engaged with a notch in the lower end of a rock arm 11 carried
25 by the ejector shaft 12, there being provided at least one of these arms 11 for each of the
ejectors.

Referring to Figs. 1 and 8 it will be observed that a handle shaft 39 has connection 30 with the ejector shaft 12 through the provision of a crank member 49 having a stud 53 engaging a fork 54' of a lever 54. The lever 54 has an arm 56 operating between the paying and registering sections of the
35 machine, said arm having a pin 66 engaged by a hook 64 supported by an arm 65 secured to the right hand end of the ejector shaft 12.

The means to actuate the selectors 20 includes, see Fig. 9, a cam 40 on the shaft 39, said cam operating in contact with a roller 41 on a lever 42. The lever 42 is connected by a link 44 with an arm 45 on an ejector bail actuating shaft 46 which is supplied with the ejector bail 47. The bail 47 is arranged beneath the right hand ends of the
45 selectors 20 and said ends are formed with hooks 48 adapted to be depressed into engagement over said bail.

50 General operation of the money paying machine.

It will be apparent that by depressing one or more of the keys 29, designated according to the decimal system used in adding machines, any predetermined amount within the range of the machine may be set up. Suitable locking means are used to hold the keys 29 depressed but said means are not described since they form no part of this invention and it is contemplated to employ any locking means of conventional type for the purpose. A depression of one or more keys 29 correspondingly depresses certain
60 selector bars 20 to engage the hooks 48 of
65

the latter with the bail 47. Now if the handle 38 is pulled forward the coöperation of the cam 49 with the lever 42 rocks the bail 47 to the right, see Fig. 1. By this action the bars 20 selected by the depressed keys 29 are likewise pulled to the right and thereby actuate certain ejector bails 22 moving certain ejectors 3 into positions with their projections 31 interlocked with adjacent ejector arms 11. The foregoing positioning of selected ejectors 3 takes place during the initial movement forward of the handle 38 and said operation is independent of the movement of the shaft 12 because the stud 66 plays loosely in the hook 64 on the arm 65, see Fig. 8. Just as the ejectors 3 have been positioned, however, the stud 66 is engaged by the inner end of the hook 64 and thereupon the rocking of the shaft 12 takes place, carrying its arms 11 forward and moving the selected ejectors 3 in paths intersecting the bottom portions of the coin holders C to discharge from the said holders coins making up the amount of money selected to be ejected from the machine.

The register attachment.

The attachment of this invention is shown best in Figs. 2 to 6 inclusive of the drawings. It comprises a register casing 100 in the ends of which is mounted a register shaft 101. The register casing 100 is formed with a downwardly extending front plate 102 and said front plate carries a plurality of casing extensions 103 seen best in Fig. 2. There is provided one of these casing extensions 103 for each coin receptacle C of the coin magazine and said casing extensions are adapted to project into the said coin holders until the rear walls of the extensions are substantially in contact with the rear walls of the holders.

Mounted on the shaft 101 are a plurality of registers, best seen in Fig. 3, each register consisting of a plurality of registering wheels 104 such as customarily employed. Furthermore each register includes an actuating disk 105 having the toothed portion 106. There is provided between the disk 105 and the units wheel of the register suitable pawl and ratchet mechanism such that a registering movement imparted to the disk 105 will be transmitted to the units registering wheel 104. In like manner there is provided between the registering wheels 120 suitable carry-over or transfer mechanism of any conventional class for the purposes for which such mechanism is commonly employed.

An actuating mechanism is utilized for each register and is the mechanism inclosed by each casing extension 103. Said mechanism includes primarily a pair of levers 107 and 108, the upper lever 107 having a sector 109 the teeth of which mesh with the toothed

portion 106 of the disk 105. At its lower end the lever 108 is formed with a lateral lug 108" disposed in the path of movement of the ejector 3 with which the particular register is to coöperate when the register attachment has been placed in position on the coin magazine. It will be apparent that when the ejector 3 moves outward in its ejecting movement as shown in Fig. 2, said 10 ejector will impart pivotal movement to the lever 108 and said movement is transmitted to the lever 107 and causes the prescribed movement of the disk 105 to actuate the associated register. Thus every time an ejector 15 3 is selected and operated a register, arranged and intended to register the movement of said ejector, is operated.

Owing to the peculiar selecting and ejector system of the money machine the predetermined sum of money set up on the keyboard of the machine by depressing the keys may, by the registers described, be divided into denominations of coins going to make up said sum of money, assuming that the 20 registers employed are unit registers and count one by one each coin or denomination of money, the registration or the ejection of which is controlled by a member 3 when the machine is used for money paying.

25 Springs 110 are used to hold the levers 108 and 107 in proper normal positions. In Fig. 2 the register illustrated is one for a double payment ejector. When the ejector 3 therefore is adjusted for a single payment the lever 108^a is operated and will give the disk 105 one increment of movement, while if the ejector 3 is adjusted to engage the lever 108", which is coaxially pivoted with respect to the lever 108, at 108^b, two increments of movement will be imparted to the lever 107 to thus register up two units on the registering wheels 104. The majority of the casing extensions 103 contain only one lever, 108, because the majority of the 30 coin holders C are intended for single coin delivery alone.

A suitable knob or handle 101^x on the shaft 101, normally locked by any desired means, is used to restore or zeroize the wheels 104.

It is to be understood that the coins ordinarily received by the holders C after use of the machine as a money paying machine, are removed when the register attachment hereinbefore described is to be used. To facilitate quick application and detachment of said register attachment it is contemplated to provide hook plates 111 at the lower ends of the outermost casing extensions 103, said hook plates being adapted to engage over studs provided on the sides of the coin magazine 116, the latter receiving at its upper portion the lower ends of the various casing extensions 103. The members 35 111 establish an interlocking connection between the lower portion of the register attachment, and a similar connection between the upper portion of the attachment and the coin magazine is provided as shown in Figs. 4 and 5. As seen in these figures a plate 113 is secured to each outermost casing extension 103 and a plate 114 is attached to the inner face of each lifting horn 115 of the coin magazine 116 in which the holders C are provided. Locking arms 117 are carried by a shaft 118 supported in the register casing 100 and one of the arms has a finger piece 119. Springs 120 hold the arms 117 in positions in which their lower ends engage or interlock in notches formed in the 40 plates 114. Obviously by pressing rearward the finger piece 119 the arms 117 will be lifted out of engagement with respect to the parts 114 and thereupon the whole register attachment may be removed bodily from 45 the magazine 116. The magazine 116 itself is supported detachably in position by suitable means whereupon it may be bodily removed either with or independently of the register attachment, this usually being done 50 by grasping the lifting horns 115 after unlocking the magazine by means forming no part of the present improvements.

I do not wish to be limited to the specific 55 form of registers illustrated herein, nor to the specific operating means employed for each register since this means may be modified at will. The primary feature of this invention consists in the employment of a register attachment capable of being placed 60 upon the coin magazine of the paying machine and movable into and out of positions in which the register operating devices coact or are not coöperatively associated with respect to the ejectors, respectively.

A cover plate 102^x may extend over all of 65 the casing extensions 102, as seen in Figs. 1 and 2.

Having thus described the invention, what 70 is claimed is:—

1. In combination, a money paying machine comprising a coin magazine including a plurality of coin holders, ejecting mechanism including ejectors associated with said coin holders for discharging money therefrom, a register attachment embodying a series of registers one for each of said coin holders, operating means for the registers, and means detachably securing the said register attachment to the coin magazine in 75 such a position that the operating means for the registers are operable by the ejectors associated with the coin holders.
2. In combination, a money paying machine comprising a coin magazine embodying a plurality of coin holders, ejector mechanism including ejectors associated with the various coin holders to discharge money therefrom, a register attachment including a plurality of register mechanisms 80

one for each coin holder, and means to detachably secure said register to the coin magazine in such a manner that the register mechanisms are received by associated coin holders and rendered operable by the ejectors coacting with said holders.

3. In combination, a money paying machine comprising a coin magazine including a plurality of coin holders, ejecting mechanism including ejectors associated with said coin holders for discharging money therefrom, a register attachment embodying a series of registers one for each of said coin holders, operating means for the registers, means detachably securing the said register attachment to the coin magazine so that the operating means for the registers are operable by the ejectors associated with the coin holders, said securing means permitting removal of the register attachment to enable use of the coin magazine as such, and means to detachably secure the coin magazine in position whereby the same and the register attachment may be bodily removed together.
4. In combination, a money paying machine embodying a coin magazine comprising a plurality of coin holders, ejector mechanism including ejectors associated with the holders to discharge money therefrom, a register attachment comprising a register casing disposed above said coin magazine, casing extensions carried by said casing and projecting into the coin holders, registers arranged in the register casing,

register operating instrumentalities disposed in the casing extensions, and means connecting said register attachment to the coin magazine in such a manner that the operating instrumentalities may coact with the ejectors.

5. In combination, a money paying machine embodying a coin magazine comprising a plurality of coin holders, ejector mechanism including ejectors associated with the holders to discharge money therefrom, a register attachment comprising a register casing disposed above said coin magazine, casing extensions carried by said casing and projecting into the coin holders, registers arranged in the register casing, register operating instrumentalities disposed in the casing extensions, means removably supporting the register attachment upon the coin magazine, said last named means including devices to interlock the lower portion of the register attachment with said coin magazine, and pivoted locking devices at the upper portion of the register attachment having detachable engagement with the upper portion of the coin magazine.

In testimony whereof I affix my signature in presence of two witnesses.

MILES H. MANN.
